FRED A. SIEVERLING, OF GREAT BEND, KANSAS

SAFETY APPARATUS FOR BOATS

Application filed April 30, 1928. Serial No. 274,067.

My invention relates to improvements in safety apparatus for boats. It is designed to enable the escape of the occupants of a sunken boat, and is particularly well adapted for use in submarines which are sunk and unable to rise to the surface.

One of the objects of my invention is to provide a novel apparatus of the kind described, which is simple, cheap to install, which is durable, not likely to get out of order, which is efficient in operation, and which will enable the occupants of a sunken boat to easily escape therefrom, or permit divers to enter the boat, without cutting through the hull and without liability of flooding the boat.

The novel features of my invention are hereinafter fully described and claimed.

In the accompanying drawings, which illustrate the preferred embodiment of my invention:

Fig. 1 is a reduced inside elevation looking at the front of the safety compartment, the inner door being shown open and the outer door closed, a portion of the hull being shown.

Fig. 2 is a similar view, the inner door being closed.

Fig. 3 is an elevation looking at the outer side of the hull, portions being broken away, and the outer door being shown closed.

Fig. 4 is an enlarged vertical sectional view on the line 4—4 of Fig. 1.

Fig. 5 is an enlarged section on the line 5—5 of Fig. 3.

Fig. 6 is a section on the line 6—6 of Fig. 4.

Fig. 7 is an enlarged section on the plane of the line 7—7 of Fig. 4.

Fig. 8 is a perspective of a crank that may be used to operate the pump.

Similar reference characters designate similar parts in the different views.

1 designates a portion of the side wall of the hull of a boat, which may be a submarine, or other vessel having air tight compartments.

In the hull 1 is provided a compartment, the outer wall 2 of which is the side wall of the hull. The floor of the compartment may be a deck 3. 4 designates the front wall of

the compartment, 5 the side walls thereof, and 6 the top of the compartment.

The outer wall 2 may be inwardly depressed, as shown, and is provided, spaced from the top 6, with a doorway 7 adapted to be closed by a door 8, which is hinged to the outer side of the wall 2 so as to swing outwardly to open, and which when closed bears against a resilient gasket 9 on the outside of the wall 2 and extending around the edges of the doorway 7. The door 8 is mounted on hinges 10, which may be usual spring hinges which tend to normally close the door.

In order that the door 8 may be closed from the interior of the hull, and at the exterior of the compartment, in case the springs 10 do not close the door, and in case the door should not be closed by anyone passing outwardly through the doorway 7, the door 8 has attached to it pivotally one end of a rod 11 the other end of which pivotally engages a block 12 fastened on a rod 13, which has one end slidably mounted in a horizontal tube 14 fastened to the wall 2. The rod 13 extends through and is slidably in a packing box 15 mounted in the front wall 4. The other end of the rod 13 is pivoted to a lever 16, the lower end of which is pivoted to a bracket 17 mounted on the wall 4.

By oscillating the lever 16, any one outside the compartment may swing the door 8 open or closed, if the outer pressure of the water against the door does not prevent its opening movement.

The front wall 4 is provided with a doorway 18, spaced, preferably, from the floor 3, and which is adapted to be closed by a door 19, which is hinged to the inner side of the wall 4 by hinges 20, which may be spring hinges tending to normally close this door. The door 19 is adapted to bear against a gasket 21 of a resilient nature fastened to the wall 4 around the doorway 18, as shown.

For tightly holding the doors 8 and 19 against the gaskets 9 and 21, there is provided a rock shaft 22, which extends through the wall 2 and through the wall 4, and has mounted on its outer end an arm 23, which is adapted to travel over and bear against a

wedge 24 on the outer side of the door 8, Fig. 6.

The rock shaft has mounted on it within the compartment an arm 25 adapted to travel over and bear against a wedge 26 on the inner side of the door 19, Fig. 6. The arms 23 and 25 are disposed at right angles to each other, so that when one is moved to the door tightening position, the other arm will be released.

10 In order that any one at the outer side of the compartment and inside the boat may swing the rock shaft 22, the latter has mounted on it, outside the compartment in front of the wall 4, an arm 27.

15 In the compartment on the wall 2 is a pressure gage 28 by which the pressure in the compartment may be ascertained. A pressure gage 29 is mounted in the door 19, and arranged to communicate with the interior of 20 the compartment, and having its dial at the outer side of the door 19, so that those in the boat, outside the compartment may ascertain the pressure in the compartment.

An electric lamp 30 may be mounted in the 25 top 6 of the compartment, Fig. 4, so as to illuminate the interior thereof.

To let water into the compartment, to equalize the internal with the external pressure outside the hull, so that the door 8 may 30 be opened, there is provided in the wall 2 a sea cock 31, which is preferably, but not necessarily self closing. The cock has in the compartment an operating lever 32 for opening the cock, and which may be used to close the 35 cock in case it sticks or is not self closing. To this lever is attached a rod 33 which extends through the wall 4 and has outside the compartment a handhold 34 by which the sea cock can be closed, in case it does not close 40 automatically, and in case that the person passing out the compartment through the doorway 7 fails to close the cock. The cock 31 has at the outside of the wall 2 an operating member 35 by which a diver can open 45 the sea cock from the outer side of the hull.

For pumping the water from the compartment, a pipe 36 extends through the top 6 to near the floor 3, and connects with a pump 37 on the top 6 and having a rotary shaft, which 50 is also an armature shaft 38 of an electric motor 39, also on the top 6.

Connected to the pump 37 is a conductor pipe 40 which extends through the hull 1 and includes an outwardly opening check valve 55 41. Two switches are respectively located within and outside the compartment, and are arranged in circuit with the motor so that the latter can be operated by the closing of either switch. The inside switch has a lever 60 42 arranged to strike a contact 43 on the inside of one side wall 5. The other switch has a lever 42' adapted to strike a contact 43' on the outer side of the wall 4.

An occupant, who may have a life preserver and an oxygen helmet, enters the com-

partment through the doorway 18, then closes the door 19, and opens the sea cock 31, and keeps it open until the inflow stops, at which time the internal pressure will equal that outside the hull. By swinging the arm 25 70 so as to release the arm 23, the door 8 may be opened to permit him to pass through the doorway 7.

The occupant of the compartment after he enters the compartment will have swung 75 the arm 25 from the upright position shown in Fig. 4 to the horizontal position against the wedge 26, thus holding the door 19 tightly closed and at the same time swinging the arm 23 off from the wedge 24 on the door 8. 80

The occupant will then pass out of the doorway 7 and will ascend through the water to the surface thereof. After leaving the compartment, however, he will see that the door 8 is closed, and will swing the arm 23 85 again into engagement with the wedge 24. Also just before leaving, he will swing the switch lever 42 into engagement with the contact 43, thus closing the circuit and causing the motor 39 to run and operate the pump, 90

37. If he should fail, however to lock the door 8 by swinging the arm 23 onto the wedge 24, or fails to swing the switch lever into the closed position, closing the door may be done by those outside the compartment and inside 95 the boat, by properly swinging the lever 16. The arm 23 may be swung to engage the wedge 24 by swinging the arm 27 to the vertical position. The inside pressure will hold the door 19 closed until the water in the compartment is pumped below the door. If the last occupant of the compartment did not close the switch lever 42 to start the pump, the other occupants of the boat can close the circuit through the motor by another switch, 100 not shown, or in case that the electric circuit is not operative, the pump shaft 38 may be turned to actuate the pump by a socket wrench 44, Fig. 8, which may be applied to the squared end 45 of the shaft, Fig. 1. 110

When the pump has operated to lower the water below the bottom of the doorway 18, another or more occupants of the boat may enter the compartment, and after closing the door 19, and swinging the arm 25 over the 115 wedge 26, may operate the sea cock lever 32 to let water into the compartment.

The water in the compartment, must be, of course, lowered therein until the pressure in the compartment is sufficiently low as to enable the door 19 to be opened. This may be determined by trial, and the gages 28 and 29 are not essential, and both may be dispensed with, if desired. When the sea cock 31 is opened, the water will continue to flow 125 into the compartment until the pressure therein equals that outside the boat, at which time the inflow will automatically cease, and the occupant may open the door 8. In like manner, when the pump has operated to 130

withdraw sufficient water from the compartment, that the pressure therein is but little more or equals the pressure in the boat outside the compartment, the door 19 may be 5 opened.

When water ceases to enter the compartment through the sea cock, the occupants thereof will open the door 8 and pass out after having closed the switch 42 and made 10 certain that the sea cock is closed. If in their haste, they should fail to close the switch and the sea cock failed to close, the occupants in the boat but outside the compartment can effect these functions, from the 15 exterior of the compartment, as has been described.

In case a diver desires access to the interior of the boat, he will swing the arm 23 to release the door 8, which, however, will still 20 be held closed by external pressure. The rock shaft 22 will swing the arm 25 to engage the wedge 26 so as to hold the door 19 tightly closed. He will then open the sea 25 cock 31 by means of the external operating member 35, and hold the cock open until the water ceases to pass into the compartment, at which time he can open the door 8 and 30 enter the compartment. He will then see that the door 8 is closed, and close the switch 42, thus operating the pump until the lowered pressure in the compartment permits the door 19 to be opened.

He can then pass further into the boat through the doorway 18.

35 Thus with the use of my invention, passage into or through the side wall of the hull of a boat may be had without having to cut a hole in the hull, and without liability of flooding the boat, thus permitting the occupants of a sunken boat to escape therefrom.

40 In cases other than with submarines, the boat will be provided with a water tight compartment outside of and with which the safety compartment, heretofore described, communicates.

45 In case of sinking of the boat, the occupants thereof may be assembled in this outside compartment, which in the drawings is the room in which the compartment described is located, and may thus be enabled to pass out of the boat through the doorways 7 and 18.

I do not limit my invention to the structure shown and described, as many modifications, 55 within the scope of the appended claims, may be made without departing from the spirit of my invention.

What I claim is:—

1. In a safety apparatus for boats, a boat 60 hull having a compartment, the outer wall of which is the wall of the hull, said outer wall and one of the inner walls of the compartment being provided respectively with doorways, two doors respectively closing said doorways, said compartment being air tight 65

when both doors are closed, means operable from inside and outside the hull and from in said compartment for admitting water into said compartment, and means having starting and stopping means operable from in 70 said compartment for pumping water from said compartment.

2. In a safety apparatus for boats, a boat hull having a compartment, the outer wall of which is one side of the hull, said outer wall 75 and one of the inner walls of the compartment having two doorways respectively, two doors respectively closing said doorways, said compartment being air tight when said doors are both closed, means having starting and stopping means operable from in 80 said compartment for pumping water from said compartment, and means releasable from outside the hull and from inside said compartment and from within said hull and exterior of said compartment for holding said outer door closed. 85

3. In a safety apparatus for boats, a boat hull having a compartment, the outer wall of which is the wall of the hull, said compartment having two doorways respectively communicating with the exterior and the interior of the hull, two doors respectively closing said doorways, the compartment being air tight when both doors are closed, means operable from within and from without the hull for admitting water from the exterior of the hull into said compartment, means having starting and stopping means operable from 90 within the said compartment for pumping water from said compartment, and means releasable from outside the hull and from inside said compartment and from within the hull and exterior of said compartment for holding said outer door closed. 95

4. In a safety apparatus for boats, a boat hull having a compartment, the outer wall of which is the wall of the hull, said compartment having two doorways respectively communicating with the exterior and the interior of the hull, two doors respectively closing said doorways, the compartment being air tight when both of said doors are closed, a sea cock communicating with said compartment, means having starting and stopping means operable from in 100 said compartment for pumping water from said compartment, and means releasable from within and from without said compartment and from outside said hull for holding either door closed when the other door is released. 105

5. In a safety apparatus for boats, a boat hull having a compartment, the outer wall of which is the wall of the hull, said compartment having two doorways respectively communicating with the exterior and interior of the hull, two doors respectively closing said doorways, the compartment being airtight when both of said doors are closed, means for admitting water into said compartment, 110 115 120 125 130

means for pumping water from said compartment, and a rock shaft extending through said hull and said compartment having means for holding said doors closed arranged to hold either door closed when the other is released, and having means in the hull exterior of said compartment for being operated to release or hold either door.

6. In a safety device for boats, a boat hull having a compartment provided with two doorways respectively communicating with the exterior and with the interior of the hull, two doors respectively closing said doorways, and a rock shaft extending through said compartment from the exterior of the hull to the interior of the hull at the outside of said compartment, said rock shaft having two parallel operating arms in said hull at the inner and outer sides respectively of said compartment, one of said arms being adapted to engage and hold the inner door closed, said rock shaft having outside the hull a third arm disposed at right angles to the other two by which the rock shaft may be swung to move said two arms to the door holding position, said third arm being adapted to engage and hold the outer door closed when the rock shaft is turned to a position in which the inner door will be released from the arm which engages it.

7. In a safety device for boats, a boat hull having a compartment, a sea cock in the wall of said hull for connecting the interior of the compartment with the exterior of the hull, and disposed below the sea level for admitting water into said compartment, and having opening and closing means operable from the exterior of the hull and provided with opening and closing means within said compartment including an operating lever, and an operating longitudinally slid able rod pivoted to said lever and extending outside said compartment into the interior of said hull, whereby said sea cock can be opened and closed from the exterior of the hull, from the interior of said hull outside said compartment, or from the interior of said compartment.

In testimony whereof I have signed my name to this specification.

50 FRED A. SIEVERLING.
